UNITED STATES PATENT OFFICE.

FRANK E. KRONENBITTER, OF MAYWOOD, ILLINOIS.

PERCOLATOR SPOUT.

Application filed August 25, 1923. Serial No. 659,292.

To all whom it may concern:

Be it known that I, FRANK E. KRONENBITTER, a citizen of the United States, residing at Maywood, in the county of Cook 5 and State of Illinois, have invented new and useful Improvements in Percolator Spouts, of which the following is a specification.

My invention relates to improvements in coffee pots, percolators and other articles 10 constructed of aluminum or other kindred material, having particular reference to improved means and methods of attaching an outlet spout to such receptacles.

Percolators, coffee pots and similar articles of aluminum are formed while the metal is soft, after which it is spun and burnished to render it hard. The spout or outlet is then applied, generally by welding, since soldering in such instances is not 15 considered dependable for permanent purposes. It has also heretofore been proposed to attach the spouts to such receptacles by means of riveting. The difficulty with the welding process of attachment of the spout 20 is that it softens the vessel at the site of the spout so that it becomes weakened and will dent or warp when the spout is struck or knocked against an object. The objection to riveting is that such procedure results in 25 cracks and crevices which gather dirt, thus rendering the vessel unsanitary and slovenly looking. In both the welding and riveting methods of attachment, it is very difficult to form the joint between the vessel 30 and the spout so that the edges of the spout will be flush with the outer surface of the vessel. It is therefore the primary object 35 of my invention to provide a novel and improved means and method of attaching 40 spouts to vessels of this character which will overcome the objections noted hereinbefore and whereby a strong and durable attachment of the spout to the vessel will be made in a highly expeditious manner without 45 however increasing the cost of the finished product.

A further object of the invention is to provide a novel and improved joint formation between the spout and the vessel whereby 50 leakage will be prohibited.

With the above and other objects in view, the invention comprises certain novel features and methods of construction and arrangement of the various parts to be hereinafter described and claimed, and in order 55

that the same may be better understood, reference is had to the accompanying drawings forming a part of this specification.

In the drawings,

Figure 1 is a fragmentary elevation of a 60 portion of a percolator showing the application of the novel spout thereto, but before it has been permanently attached;

Fig. 2 is a front elevation of the spout applied to the vessel; 65

Fig. 3 is an elevation of the spout supporting wall of the vessel from the exterior thereof, and illustrating the spout supporting means;

Fig. 4 is a sectional view taken on the 70 line 4-4 of Fig. 1;

Fig. 5 is a section on the line 5-5 of Fig. 2;

Fig. 6 is a view similar to Fig. 3 but illustrating a slightly modified form of the 75 invention;

Fig. 7 is a sectional view taken on the line 7-7 of Fig. 6;

Fig. 8 is a perspective view of the spout 80 removed, and

Fig. 9 is a sectional detail of the joint between the spout and vessel.

Referring specifically to drawings, wherein for the purpose of illustration, the preferred embodiment of the invention is disclosed, and in which like reference characters have been used to designate similar parts throughout all views, numeral 10 denotes the body portion of a percolator, which is preferably formed of aluminum. 85 In one of the walls of the vessel a hole 11 is cut, the marginal edges of which are turned back as shown at 12 in Fig. 3 to form a continuous substantially U-shaped flange or guide for the reception of a spout 90 14, it being noted that the opposed portions of the flange are spread outwardly to give the same a wedge-like function when the spout is applied as will presently appear. It will be readily apparent from Fig. 3 that the hole 11 may be so formed that a depending tongue 13 will be formed to prevent the liquid within the percolator from coming out too fast. 95

The open back of the spout 14 is being provided with an out-turned marginal substantially U-shaped flange 14^a which is reverted inwardly as shown at 14^b, thus forming between the outward and reverted portions 14^a and 14^b, respectively, a groove 14^c 110

for the reception of the edge of the out-turned U-shaped spout carrying flange 12 of the percolater previously described.

From the foregoing it will be apparent 5 that the flange 12 may be engaged in the groove 14^c and the spout 14 moved thereon to the relation shown in Figs. 1 and 4. This having been accomplished, the next step is to so clamp the spout to the flange 12 and 10 body of the vessel as to present a smooth and attractive joint and one which will be strong, durable and leak-proof.

The above result is attained by the employment of suitable dies, the application 15 and use of which indents the wall of the vessel adjacent the out-turned flange 12 inwardly as shown at 15 in Figs. 7 and 9. This results in the lateral portion 14^a of the spout 14 being located flush with the 20 outer surface of the vessel. A liquid tight joint will be provided, but in order to make doubly sure of this, it is best to place a thin layer of litharge or similar substance within the groove 14^c of the spout 14 and also 25 in the groove formed by the flange 12 and the body of the vessel 10 preparatory to locating the spout as shown in Figs. 4 and 9. Then, upon the application of the dies to 30 form the joint as shown in Fig. 9, the associated flanges will be securely clamped together and the litharge will prevent any possibility of leakage of the contents of the vessel out through the spout joint.

In Figs. 6 and 7 it will be noted that the 35 tongue 13 is formed considerably longer than in Fig. 3. In this embodiment, it is not necessary to cut a hole 11 but merely to make a U-shaped slit in the front of the vessel and bend marginal edges outwardly. 40 This tongue 13^a of Fig. 6 may be apertured as shown at 13^b and a pair of marginal stiffening ribs 13^c are preferably provided, which tend to keep the tongue rigid and in engagement with the adjacent surface of 45 the spout 14, as clearly shown in dotted lines in Fig. 7.

When the short tongue 13 is employed, it is often necessary in order to properly strain the contents of the vessel or to keep 50 the aroma from escaping therefrom to provide a closure slide or strainer member 16, as the case may be, which is indicated in Fig. 5 as being inserted between the tongue 13 and the adjacent lateral flange of the

spout 14. The tongue 13 has a tendency to 55 urge the member 16 upwardly against the spout for thus keeping the same in place but at the same time permitting it to be slidably removed.

It might here be stated that a tight externally smooth joint as above described is especially desirable where the vessel is of aluminum since such articles are not enameled or otherwise covered to fill in cracks and crevices which would occur in other forms of joints to gather dirt or render the container likely to leak. The spout 14 may be quickly applied and upon the application of stamping dies the attached portion 70 of the spout will lie flush with the outer surface of the vessel wall, the joint being hardly perceptible. But one stroke of the dies is necessary to secure the result and the double groove construction at the site of the joint effectually prevents leakage 75 and gives four thicknesses of metal to assure rigidity.

In accordance with the patent statutes I have described and illustrated herein the preferred embodiment of my invention but 80 it will be distinctly understood that I do not propose to limit myself strictly to the details set forth since various changes and modifications thereof will immediately suggest themselves to those skilled in the art 85 without departing from the spirit of my invention, the scope of which is defined by the following claim.

I claim:

An improved vessel of the class described 90 including a body having a U-shaped slit provided with out turned ends and formed adjacent the top of the side wall of said vessel, the material on the outer side of the slit being rolled outwardly throughout the 95 length of the slit to form a flange on the exterior of the body for engagement by a spout flange, the material within said slit forming a downwardly extending tongue 100 integral with the body at its upper end, said tongue being provided with a multiplicity of perforations therein, said tongue further having stiffening ribs adjacent its sides.

In testimony whereof I affix my signature. 105

FRANK E. KRONENBITTER.
